(57) **CLAIM**

The ornamental design for a garden armchair, as shown and described.

DESCRIPTION

FIG. 1 is a front elevational view of a first embodiment of my series relating to a garden armchair;

FIG. 2 is a rear elevational view of FIG. 1;

FIG. 3 is a top plan view of FIG. 1;

FIG. 4 is a bottom plan view of FIG. 1;

FIG. 5 is a side elevational view of FIG. 1, the elevational view of the other side being a mirror image and, therefore, not shown;

FIG. 6 is a front elevational view of a second embodiment of my series relating to a garden armchair;

FIG. 7 is a rear elevational view of FIG. 6;

FIG. 8 is a top plan view of FIG. 6;

FIG. 9 is a bottom plan view of FIG. 6;

FIG. 10 is a side elevational view of FIG. 6, the elevational view of the other side being a mirror image and, therefore, not shown;

FIG. 11 is a front elevational view of a third embodiment of my series relating to a garden armchair;

FIG. 12 is a rear elevational view of FIG. 11;

FIG. 13 is a top plan view of FIG. 11;

FIG. 14 is a bottom plan view of FIG. 11; and,

FIG. 15 is a side elevational view of FIG. 11, the elevational view of the other side being a mirror image and, therefore, not shown.
